UNITED STATES PATENT OFFICE.

JUAN HARPER, OF SANTIAGO, CHILE.

RIBBON-CARRIER FOR TYPE-WRITING MACHINES.

1,009,305.

Specification of Letters Patent. Patented Nov. 21, 1911.

Application filed August 4, 1911. Serial No. 642,382.

To all whom it may concern:

Be it known that I, JUAN HARPER, a citizen of the Republic of Chile, and resident of Santiago, Chile, have invented a new and useful Ribbon-Carrier for Type-Writing Machines, of which the following is a specification.

My invention relates to a ribbon carrier for typewriting machines, with the object in view of providing a carrier which will permit the ribbon to be shifted edgewise to bring longitudinal sections of the ribbon into position to receive the immediate impact of the type.

15 My invention is particularly well adapted to use in connection with what is known in the art as the "Oliver" typewriter, although I do not wish to limit myself to its use with this particular machine.

20 In the accompanying drawings, Figure 1 is a top plan view of the ribbon carrier as it appears in use. Fig. 2 is a view of the same in side elevation. Fig. 3 is a longitudinal section in the plane of the line A—A of Fig. 1. Fig. 4 is a bottom plan view. Fig. 5 is a transverse section in the plane of the line B—B of Fig. 2. Fig. 6 is a top plan view of a modified form. Fig. 7 is a longitudinal section in the plane of the line C—C 80 of Fig. 6, and Fig. 8 is a bottom plan view of the same.

The support for the ribbon carrier proper is here shown as the Oliver ribbon carrier support and consists of parallel links 1 and 35 2 fulcrumed in a support 3 and connected at their upper ends by a plate 4. This forms no part of my present invention except so far as it serves as a suitable support for the ribbon carrier proper.

40 The ribbon carrier proper consists of a plate 5 from one end of which project branches 6 and 7, the outer ends of which are turned over and under, as shown at 8 and 9 to form elongated openings 10 through which the ribbon 11 passes. At or near its opposite end, the plate 5 is clamped to the support 4 by means of a T-bolt 12, the head 13 of which crosses an elongated slot 14 in the support 4, and the threaded 50 end of which receives a milled thumb-nut 15, as clearly shown in the several figures. The plate 5 is further guided on the support 4 by means of a T-screw 16, the head 17 of which overlaps the walls of an elongated slot 18, see Fig. 4, and the shank of which is squared, as shown at 19, to prevent the

screw from turning in the slot 18. The screw 16 is screwed into the plate 5.

On the plate 5, there are indicator marks, denoted by 20, 21, and an index pointer 22, 60 uprising from the support 4, and reaching over the edge of the plate 5, serves to lock the ribbon carrier in the position desired to shift the ribbon laterally from one position to another, the two positions being shown 65 in Fig. 1, the one in full lines and the other in dotted lines.

The modified form shown in Figs. 6 to 8 inclusive, shows the body of the carrier consisting of a plate 23 provided with branches 70 as hereinbefore explained and having secured to its upper face a spring tongue 24, the heel end of which is held securely to the plate 23 by means of a T-rivet 25, the head of which overlaps the walls of an elongated 75 slot 26 in the support and the shank of which is squared to slide along the slot 26, the free end of the said spring 24 being provided with a pin 27 set therein, which pin projects downwardly through the plate 23 80 and is adapted to enter one or another of the three holes 28, 29, 30, formed in the support. These three holes 28, 29, 30 correspond to the three positions indicated by the marks 31, 32, 33, on the upper face of 85 the plate 23 and serve to adjust the ribbon 11 in position to have the type strike it along a central line and along lines on either side of a central line. In this form the index pointer 34 and an overlapping lip or guide 90 35, see Fig. 6, are formed at the opposite ends of a narrow strip of material 36 which is secured to the under side of the support by means of screws 37, 38.

It is obvious that the structure shown in 95 Figs. 1 to 5 inclusive will admit of shifting the ribbon 11 laterally not only into the two positions indicated by the marks 20 and 21 on the face of the plate, but also into as many positions as may be desired since the 100 slots 14 and 18 are continuous instead of being articulated as in the modified form.

The ribbon carrier may be detached at pleasure when desired, in the first instance by removing the milled nut 15 and withdrawing the screw-bolt 12, when the support may be swung at an angle of 90° to permit the head 17 of the guide screw to pass upwardly through the slot 18. In the modified form the piece 36 may be removed by 110 unscrewing the screws 37, 38 and then by withdrawing the pin 27, the carrier may be

swung to permit the head of the guide screw or rivet to pass through the slot 26.

What I claim is:

1. A ribbon carrier for typewriting machines comprising a carrier proper provided with loops for receiving the ribbon, a support for the carrier provided with an elongated slot, a T-shaped guide projecting from and fixed to the carrier proper for directing the carrier proper along its support and holding it on its support and a device for locking the carrier proper in different adjusted positions.

2. A ribbon carrier for typewriting machines comprising a carrier proper provided with arms for receiving the ribbon and with a scale to indicate different adjustments in

combination with a support for the carrier, the latter provided with elongated slots and with an index pointer, a guide extending through one of the slots and a clamping device extending through another of the slots whereby the carrier may be adjusted in different indicated positions and clamped in those positions.

In testimony that I claim the foregoing as my invention, I have signed my name in presence of two witnesses, this first day of July A. D. 1911.

JUAN HARPER.
